DESIGN.

E. M. QUINT.
TOURIST GUIDE BOARD.
APPLICATION FILED DEC. 21, 1920.

59,924.

Patented Dec. 6, 1921.

Inventor:

Edgar Minot Quint.

UNITED STATES PATENT OFFICE.

EDGAR MINOT QUINT, OF CONCORD, NEW HAMPSHIRE.

DESIGN FOR A TOURIST GUIDE-BOARD.

59,924.

Specification for Design.

Patented Dec. 6, 1921.

Application filed December 21, 1920. Serial No. 432,367. Term of patent 14 years.

To all whom it may concern:

Be it known that I, EDGAR MINOT QUINT, a citizen of the United States, residing at Concord, in the county of Merrimac and State of New Hampshire, have invented a new, original, and ornamental Design for Tourist Guide-Boards, of which the following is a specification, reference being had to the accompanying drawing, forming a part thereof.

The idea of these tourist guide boards for the States and Territories of the United States, is to furnish a simple and easily understood method of presenting the different State roads and trails painted in their

banded colors, principal cities, towns and other points of interest such as mountains, lakes, summer resorts, mileage between points, etc.

The figure is a plan view of a tourist guide board, showing my new design. The lines on map represent State roads and trails, the dots represent the location of principal cities.

The superstructure is designed to receive the map or outline of any State or Territory in the United States.

I claim:

The ornamental design for a tourist guide board, as shown and described.

EDGAR MINOT QUINT.
